UNITED STATES PATENT OFFICE

153,216

DESIGN FOR AN EYEGLASS LENS

Julius E. Hansen, Providence, R. I., assignor to
Bay State Optical Company, Attleboro, Mass.,
a corporation of Maine

Application January 17, 1947, Serial No. 136,195

Term of patent 14 years

(Cl. D57—1)

To all whom it may concern:

Be it known that I, Julius E. Hansen, a citizen of the United States and a resident of Providence, in the county of Providence, State of Rhode Island, have invented a new, original, and ornamental Design for an Eyeglass Lens, of which the following is a specification, reference being had to the accompanying drawing, forming a part thereof.

In the drawing,

Figure 1 is a front elevation; and

Figure 2 is a top plan view of an eyeglass lens, showing my new design.

The essential feature of my design for an eyeglass lens resides in the three-sector configuration of the lens as illustrated and in making the opti-

cal center substantially equi-distant from the centers of the three sectors.

I claim:

The ornamental design for an eyeglass lens, substantially as shown and described.

JULIUS E. HANSEN.
